UNITED STATES PATENT OFFICE.

NELSON FLOYDE MATTESON, OF WASHINGTON, DISTRICT OF COLUMBIA.

LATCH.

Application filed February 27, 1922. Serial No. 539,492.

To all whom it may concern:

Be it known that I, NELSON FLOYDE MATTESON, a citizen of the United States of America, residing at Washington, in the 5 District of Columbia, have invented certain new and useful Improvements in Latches, of which the following is a specification.

This invention relates to certain new and useful improvements in latches for swinging doors particularly serviceable in connection with the doors of automobiles.

In the usual forms of latches for automobile doors, a sliding bolt is normally spring projected and so held until manually retracted so that oftentimes a person's clothing is torn on the projecting bolt when getting in and out of the automobile. In addition to this, these projecting latch bolts prevent ready closing of the door and in order 20 to effect latching of the door in closed position, the door must be slammed or swung closed with considerable force to overcome the action of the spring which projects the sliding bolt and causes the bolt to be forced 25 to retracted position by engagement of a beveled face of the bolt with the keeper. This forceful closing of the door causes considerable annoying jars and undesirable loud noise.

It is the primary object of the present invention to provide a latch for automobile doors of the spring projected bolt type wherein provision is made for automatically retaining the bolt retracted when the same 35 is manually moved to its retracted position and to make provision for automatic release of the retracted bolt by a slight impact which occurs upon closing the door with very little force.

Another object of the invention is to provide means to regulate the degree of force necessary in swinging the door to a closed position while insuring release of the retracted bolt so that the device may meet with 45 the conditions and requirements which may arise with respect to different forms of automobiles and whereby the invention will meet with all of the requirements for a successful commercial use.

With the above general objects in view and others that will appear as the nature of

the invention is better understood, the invention consists in the novel form, combination and arrangement of parts hereinafter more fully described in connection with the accompanying drawings in which like reference characters designate similar parts throughout the views.

In the drawing,

Figure 1 is a fragmentary perspective inside view of an automobile door partly broken away, and equipped with a latch constructed in accordance with the present invention,

Figure 2 is a side elevational view, partly broken away of the latch shown in Figure 1,

Figure 3 is a horizontal sectional view taken upon line III—III of Figure 2,

Figure 4 is a vertical sectional view taken upon line IV—IV of Figure 3,

Figure 5 is a view similar to Figure 2 with the sliding bolt retracted, and

Figure 6 is a horizontal sectional view taken upon line VI—VI of Figure 5.

Referring more in detail to the several views, the present invention is shown embodied in a door latch of the sliding bolt type wherein a two-part casing is provided embodying a relatively large plate 5 having one end bent at right angles as at 6 or 70 formed in this relation, the plate 5 being provided with suitable corner openings 7 to admit screws 8 or the like for fastening the casing to the usual door 9 with the portion 6 of the plate flush with the vertical edge of 75 the door which is free and the portion 5 flush with the inner wall of the door which is usually covered with heavy leather or the like as illustrated in Figure 1. The other member of the casing comprises a smaller 80 somewhat pan-shaped sheet metal member 10 with projecting lugs riveted in suitable openings in the plate member 5 as at 11 so as to provide a bolt chamber 12 in which is positioned a horizontal sliding latch bolt 13 85 which is normally projected through an opening 14 in the plate portion 6 as shown in Figures 2, 3 and 4 for engagement with the usual keeper to hold the door closed, by means of a spring 15. The 90 bolt 13 is shown as slidably guided by means of a lug 16 thereon projecting through a

100

horizontal elongated slot 17 in the casing member 10, and the bolt 13 also projects through a slot in the outer side of the member 10 so that the outer end of the bolt is effectively held against upward or downward lateral movement when projected or retracted.

The spring 15 is shown as of the coiled type having its inner end suitably anchored 19 to a post 18 rigid with the plate member 5 and having its outer end extended laterally and bearing against the outer wall of a slot 19 provided in the bolt 13 whereby said spring forcibly projects said bolt. This outer 15 wall of the slot 19 is engaged as at 20 by the outer end of the spring 15, and said spring exerts a force in a direction to project the bolt 13. The bolt is laterally tilttable and will be forced laterally in a manner to be 20 described, when entirely retracted so as to engage behind the plate portion 6 as shown in Figure 6, automatically, and so that the bolt will remain retracted and out of the way in order that tearing of the clothes thereon 25 will not occur. It is noted that the direction of movement of the bolt 13 laterally is the same as the direction of the movement of the door in opening so that when the door is closed the slight jar which occurs will cause 30 lateral movement of the bolt in the opposite direction for aligning the bolt with the slot or opening 14 and allowing said bolt to be immediately projected into the keeper by spring 15. In this way, there is no need of 35 forceful slamming of the door to effect latching of the same.

In order to insure lateral movement of the bolt 13 in some forms of latches to cause the bolt to engage behind the plate portion 6 40 as shown in Fig. 6 when said bolt is entirely retracted through the opening or slot 14, a spring-pressed plunger 21 may be provided and as shown, this plunger and its spring is located within an oblique opening 45 provided in the outer end of the bolt 13 and having its outer end engaging a screw plug 22 which is adjustably threaded in 50 said opening, while the inner end of the plunger engages the inner face of the plate portion 5. By adjusting the plug 22, the 55 force of the spring 21 may be regulated to suit the particular conditions under which the latch is being employed, and as shown, the spring 21 is provided in an oblique opening in the bolt so that the inner end of the plunger will at all times be positioned to bear upon the plate member 5.

In order to permit manual retraction of the bolt 13, a vertical shaft 23 may be pivoted 60 in suitable bearings 24 provided on the plate portion 5, which shaft is formed with a lateral extension at its upper end to provide a handle 25 and has a lug or integral arm 26 extending laterally therefrom at its lower end, which arm or lug

26 is disposed to engage the outer end of the bolt enlargement or lug 16 as shown in Figure 3 and to play within the slot 19 of said bolt. It will be apparent that upon rotation of the shaft 23 with the parts positioned as shown in Figures 2 to 4 inclusive, the bolt 13 may be retracted to the position of Figure 6 by reason of the engagement of the arm 26 with the enlargement 16 of said bolt, the bolt 13 being immediately automatically moved laterally in one direction to engage behind the plate member 6 when the outer end of said bolt passes the inner edge of the adjacent wall of the opening 14. The bolt is retained retracted until the door 80 is closed and when the latter occurs the slight jar causes lateral movement of the bolt in the opposite direction so that the bolt and opening 14 are alined and the spring 15 immediately projects said bolt 85 outwardly through the opening 14 to engage the usual keeper, not shown, for holding the door closed.

As the end of the spring 15 which engages the bolt 13 is located outwardly of the transverse center and inwardly of the longitudinal vertical center of the bolt 13, and the operating lug 26 is located inwardly of 90 said transverse center and engages the enlargement 16 outwardly of said longitudinal center, the bolt 13 is naturally tilted laterally to engage behind the plate member 6, when retracted. The spring-pressed plunger 21 95 may be employed to make this more positive or may be employed when the specific structure of the latch is such as to not incur this natural tendency of the bolt to tilt when retracted.

It will thus be seen that the spirit of the present invention is to provide a door latch 100 wherein provision is made for automatically holding the latch bolt in retracted position operable upon sudden stopping of the door in moving to closed position for automatically releasing the bolt and allowing the 105 latter to be projected.

From the foregoing description, it is believed that the construction and operation of the present invention will be understood and appreciated by those skilled in the art. 110

Minor changes may be made without departing from the spirit and scope of the invention as claimed.

What is claimed as new is:—

1. In a latch for doors, a spring projected bolt, means to manually retract said bolt to door releasing position, and jar-releasable means enclosed by the bolt to automatically retain the bolt retracted providing for the automatic release of the bolt for projection 125 upon sudden stopping of the door in closing.

2. A door latch embodying a member displaceable laterally in one direction by jarring and further embodying a spring projected bolt having manual retracting means, 130

- means to automatically laterally displace said member in another direction upon retraction of the bolt, and means for automatically holding the bolt retracted, when 5 said member is laterally displaced in said other direction, whereby lateral displacement of said member in the first named direction will be automatically had upon sudden stopping of the door in closing for re- 10 leasing the bolt and permitting the same to be projected, said laterally displaceable member comprising said bolt, and means to regulate the force of said means for displacing the member in said other direction.
- 15 3. A latch for doors comprising a spring projected bolt having means for manually retracting the same, and means extending transversely through the bolt to automatically retain the bolt in retracted position 20 automatically releasable for permitting projection of the bolt upon sudden stopping of the door in closing, said latch being constructed to provide for release of the bolt when in retracted position due entirely to 25 the momentum of a displaceable member of the latch.
4. In a door latch wherein a casing in- 30 closes a normally projected tensioned bolt, wherein manually operable means is asso- ciated with the bolt for retracting the same and cooperating therewith in a manner to cause lateral shifting movement of the bolt during retraction with the nose of the bolt positioned for engagement with the casing 35 to hold the bolt retracted, and wherein the bolt nose is released from the casing for pro- jection upon the occurrence of a jar inci- 40 dent to the closing of the door, means em- bedded in the bolt and engaging the casing to effect positive lateral shifting move- 45 ment of the bolt during retraction thereof.
5. In a door latch wherein a casing in- 50 closes a normally projected tensioned bolt, wherein manually operable means is asso- ciated with the bolt for retracting the same and cooperating therewith in a manner to cause lateral shifting movement of the bolt during retraction with the nose of the bolt positioned for engagement with the casing 55 to hold the bolt retracted, and wherein the bolt nose is released from the casing for pro- jection upon the occurrence of a jar inci- 60 dent to the closing of the door, tensioned means embedded in the bolt and engaging the casing to effect positive lateral shifting move- 65 ment of the bolt during retraction thereof.
6. In a door latch wherein a casing in- 70 closes a normally projected tensioned bolt, wherein manually operable means is asso- ciated with the bolt for retracting the same and cooperating therewith in a manner to cause lateral shifting movement of the bolt during retraction with the nose of the bolt positioned for engagement with the cas- 75 ing to hold the bolt retracted, and wherein the bolt nose is released from the casing for projection upon the occurrence of a jar incident to the closing of the door; ten- sioned means carried by the bolt and in con- 80 stant engagement with the casing to effect positive lateral shifting movement of the bolt during retraction thereof.
7. In a door latch wherein a casing in- 85 closes a normally projected tensioned bolt, wherein manually operable means is asso- ciated with the bolt for retracting the same and cooperating therewith in a manner to cause lateral shifting movement of the bolt during retraction with the nose of the bolt positioned for engagement with the casing to hold the bolt retracted, and wherein the bolt nose is released from the casing for projection upon the occurrence of a jar incident to the closing of the door, tensioned means associated with the bolt and casing to effect positive lateral shifting movement of the bolt during retraction thereof and so disposed that the lateral shifting movement of the bolt is on a line at an angle to the longitudinal axis of the tensioned means.
8. In a door latch wherein a casing in- 90 closes a normally projected tensioned bolt, wherein manually operable means is asso- ciated with the bolt for retracting the same and cooperating therewith in a manner to cause lateral shifting movement of the bolt during retraction with the nose of the bolt positioned for engagement with the casing to hold the bolt retracted, and wherein the bolt nose is released from the casing for projection upon the occurrence of a jar incident to the closing of the door, means to effect positive lateral shifting movement of the bolt during retraction thereof including a tensioned plunger slidably carried by the bolt and in constant engagement with the casing.
9. In a door latch wherein a casing in- 95 closes a normally projected tensioned bolt, wherein manually operable means is asso- ciated with the bolt for retracting the same and cooperating therewith in a manner to cause lateral shifting movement of the bolt during retraction with the nose of the bolt positioned for engagement with the casing to hold the bolt retracted, and wherein the bolt nose is released from the casing for projection upon the occurrence of a jar incident to the closing of the door, means to effect positive lateral shifting movement of the bolt during retraction thereof including a tensioned plunger slidably carried by the bolt and in constant engagement with the casing.
10. In a door latch wherein a casing in- 100 closes a normally projected tensioned bolt, wherein manually operable means is asso- ciated with the bolt for retracting the same and cooperating therewith in a manner to cause lateral shifting movement of the bolt during retraction with the nose of the bolt positioned for engagement with the cas- 105 ing to hold the bolt retracted, and wherein the bolt nose is released from the casing for projection upon the occurrence of a jar incident to the closing of the door, means to effect positive lateral shifting movement of the bolt during retraction thereof including an adjustably tensioned plunger carried by the bolt and engaging the casing.
11. In a door latch wherein a casing in- 110 closes a normally projected tensioned bolt, wherein manually operable means is asso- ciated with the bolt for retracting the same and cooperating therewith in a manner to cause lateral shifting movement of the bolt during retraction with the nose of the bolt positioned for engagement with the cas- 115 ing to hold the bolt retracted, and wherein the bolt nose is released from the casing for projection upon the occurrence of a jar incident to the closing of the door, means to effect positive lateral shifting movement of the bolt during retraction thereof including an adjustably tensioned plunger carried by the bolt and engaging the casing.
12. In a door latch wherein a casing in- 120 closes a normally projected tensioned bolt, wherein manually operable means is asso- ciated with the bolt for retracting the same and cooperating therewith in a manner to cause lateral shifting movement of the bolt during retraction with the nose of the bolt positioned for engagement with the cas- 125 ing to hold the bolt retracted, and wherein the bolt nose is released from the casing for projection upon the occurrence of a jar incident to the closing of the door, means to effect positive lateral shifting movement of the bolt during retraction thereof including an adjustably tensioned plunger carried by the bolt and engaging the casing.

during retraction with the nose of the bolt positioned for engagement with the casing to hold the bolt retracted, and wherein the bolt nose is released from the casing for projection upon the occurrence of a jar incident to the closing of the door, means to effect positive lateral shifting movement of

the bolt during retraction thereof including a tensioned plunger carried by the bolt and engaging the casing, and means for varying the tension on the plunger. 10

In testimony whereof I affix my signature.

NELSON FLOYDE MATTESON.
